Company, Madison, Wis., a corporation of Wisconsin

Application September 6, 1955, Serial No. 37,790

Term of patent 14 years

(Cl. D57—1)

FIG.1

Fig. 1 is a top plan view of a pair of goggles showing the side shields in partially extended position and showing my new design;

Fig. 2 is a side view of one of the side shields viewed from the right side of Figure 1;

Fig. 3 is an inside view of the side shield shown at the left of Figure 1; and

Fig. 4 is a top perspective view thereof, showing the side shields in operating position and with the headband removed.

The dominant feature of my design resides in the portions shown in full lines.

I claim:

The ornamental design for a pair of goggles, substantially as shown and described.
